US00D512698S

(12) **United States Design Patent** (10) Patent No.: **US D512,698 S**
Augenbraun et al. (45) Date of Patent: **** Dec. 13, 2005**

(54) **VIDEO PHONE**

(75) Inventors: **Joseph Augenbraun**, Princeton, NJ (US); **Dana Ainsworth**, Yardley, PA (US); **Joel Boyarski**, Philadelphia, PA (US); **Randall Gort**, Malvern, PA (US); **Hal Krisbergh**, Rydal, PA (US); **Jamie Press**, Lansdale, PA (US); **Jeanne Ritts**, Beverly, NJ (US); **David Wachob**, New Hope, PA (US)

(73) Assignee: **Worldgate Service, Inc.**, Trevose, PA (US)

(**) Term: **14 Years**

(21) Appl. No.: **29/193,376**

(22) Filed: **Nov. 10, 2003**

(51) LOC (6) Cl. **14-03**

(52) U.S. Cl. **D14/130; D14/129; D14/375**

(58) Field of Search **D14/149-151, D14/147-148, 251-253, 144, 143, 130, 329, 330, 434, 140, 142, 375, 129, 126; 379/419, 428.01-428.04, 440; D13/107, 108; D21/517; 348/836, 14.01; 455/557**
